CLAIM

The ornamental design for an elevating speaker for use in bathtub, design as shown and described.

DESCRIPTION

FIG. 1 is a top, front, right perspective view of a elevating speaker for use in bathtub.

FIG. 2 is a front view of the elevating speaker for use in bathtub, design of FIG. 1.

FIG. 3 is a rear view of the elevating speaker for use in bathtub, design of FIG. 2.

FIG. 4 is a left side view of the elevating speaker for use in bathtub, design of FIG. 2.

FIG. 5 is a right side view of the elevating speaker for use in bathtub, design of FIG. 2.

FIG. 6 is a top view of the elevating speaker for use in bathtub, design of FIG. 2.

FIG. 7 is a bottom view of the elevating speaker for use in bathtub, design of FIG. 2.

FIG. 8 is a top, front, right perspective view of descending the speaker of an elevating speaker for use in bathtub; and, FIG. 9 is an enlarged view of FIG. 7 of the elevating speaker for use in bathtub.

The broken lines shown are included for the purpose of illustrating portions of the elevating speaker for use in bathtub that form no part of the claim.

1 Claim, 9 Drawing Sheets
